Primary Examiner — Lucy Lieberman(74) *Attorney, Agent, or Firm* — Ruben Alcoba, Esq(57) **CLAIM**

I claim the ornamental design for the jeweled watch, as shown and described.

DESCRIPTION

FIG. 1 is a front perspective view of the jeweled watch;
 FIG. 2 is a front elevation view of the jeweled watch;
 FIG. 3 is a rear elevation view of the jeweled watch;
 FIG. 4 is a top elevation view of the jeweled watch;
 FIG. 5 is a bottom elevation view of the jeweled watch; and,
 FIG. 6 is a left side elevation view of the jeweled watch.
 Note, the right side elevation view of the jeweled watch is not shown for it is a mirror exact of the left side elevation view shown in FIG. 6.

The broken lines in the drawings are used to show portions of the jeweled watch that do not form part of the claimed design. A jeweled watch that has clear transparent window chambers on all sides (see FIGS. 1-6). Free-floating stones are in chambers. The free-floating stones move within the chambers as the jeweled watch is moved.
